UNITED STATES PATENT OFFICE

OTTO M. SUMMERS, OF DAYTON, OHIO, ASSIGNOR TO FRIGIDAIRE CORPORATION, OF DAYTON, OHIO, A CORPORATION OF DELAWARE

REFRIGERATING APPARATUS

Application filed July 31, 1929. Serial No. 382,516.

This invention relates to refrigerating apparatus and particularly to cooling units for such apparatus.

One of the objects of the present invention is to provide an improved evaporator which is smooth and readily cleaned and of pleasing appearance.

Another object of the invention is to provide an improved cooling unit preferably constructed of sheet metal, which provides intimate thermal contact between the substance to be cooled and the refrigerant therein.

More specifically it is an object of the present invention to construct a sectional sheet metal evaporator comprising portions which can be removed and replaced should they become damaged.

Further objects and advantages of the present invention will be apparent from the following description, reference being had to the accompanying drawings, wherein a preferred form of the present invention is clearly shown. In the drawings:

Fig. 1 is a view of my improved evaporator installed in a refrigerator of the household type.

Fig. 2 is a front view of the evaporator having the ice trays removed therefrom.

Fig. 3 is a side view of the evaporator.

Fig. 4 is an enlarged cross sectional view of the evaporator taken on the line 4—4 of Fig. 3.

Fig. 5 is a view taken in the line 5—5 of Fig. 4, showing a method of fastening a back onto the evaporator.

Fig. 6 is a view of a plate employed in the construction of the evaporator.

Fig. 7 is a view of the plate shown in Fig. 6 after being formed into the desired shape.

Fig. 8 is a view of another plate employed in the construction of the evaporator, and

Fig. 9 is a view of the plate shown in Fig. 8 after being formed into the desired shape.

Referring to the drawings, Fig. 1 discloses a section of a cabinet illustrating the installation of a cooling unit made in accordance with the invention. The cooling unit is herein shown as an evaporator including a header or tank 10 containing a float valve mecha-

nism for maintaining a predetermined liquid refrigerant level therein. The float valve mechanism may be of the type shown in the patent to R. G. Osborn 1,556,708 issued October 13, 1925. The evaporator also includes 55 hollow wall sheet metal members, which will be more fully described herein, connected to the header 10 and depending therefrom to provide the enclosure 11. Brackets 13 and 14 support the evaporator in the cabinet and 60 are attached to the inner lining 15 of same. Also disclosed is the insulation 16 and the outer frame work or covering 17 for the installation. An L-shaped partition 18 provides a compartment for the evaporator and 65 has openings 20 and 21 located therein for the circulation of air thru the compartment for cooling the rest of the food chamber or cabinet. The bonnet 22 prevents any dripping of condensed moisture from the evaporator dripping on the food. Connections 23 and 24 extend to any type of refrigerant supply apparatus such as that disclosed in the patent to H. B. Hull 1,648,178 issued November 8, 1927. It is obvious of course that 75 the type of refrigerator or refrigerant supply apparatus is a matter of choice.

The header or boiler 10 is adapted to contain a liquid refrigerant preferably sulphur dioxide. The boiler is provided with flattened portions 31 having a hole in the center thereof. The collar 32 is preferably sealed on the inside circumference of the holes thru the flattened portions 31. The boiler 10 and refrigerant pipe connections 23 and 24 secured thereto are covered with a metal of high 80 polishability, preferably chromium altho others such as nickel might be used. This surface, which is preferably plated, constitutes a smooth, hard, non-rusting finish which 85 is very easily cleaned.

The enclosure 11 depending from the boiler 10 is provided by hollow wall members 35 which form the freezing zone adapted to receive ice making receptacles such as ice trays. In the preferred embodiment the hollow wall members are formed of an outer sheet metal wall 36 and an inner sheet metal wall 37. These walls are preferably formed, welded 90 together and detachably connected to the 100

boiler 10 to provide complementary wall portions of the enclosure 11 as disclosed in the drawings. Each of the hollow wall members 35 comprises a flat plate having a raised portion 38 formed therein (see Fig. 6). This plate is then folded along the line A—A to provide the outer wall 36 of member 35 as shown in Fig. 7. The inner wall 37 of each hollow wall member 35 is provided by forming a raised portion 39 in a flat plate (see Fig. 8) and folding this plate along the lines B—B, C—C, D—D, E—E, F—F, G—G, H—H, and I—I to produce the projections 40 as shown in Fig. 9. The plates 36 and 37 are then welded together along their edges so as to provide one of the complementary unitary structures which are connected to the boiler 10 as shown in the drawings. It is apparent that the members 35 are identical but are reversed when attached to the boiler 10 to provide refrigerant expansion chambers separate from one another and complementary wall portions of the enclosure 11. The upper ends of the members 35 and the projections 40 formed on these members may abut each other or may be spaced as shown in the drawings.

The projections 40 provided on the plate 37 divides the enclosure or freezing zone 11 into compartments 41, 42 and 43 and also serve as shelves for receiving ice trays. The chambers formed in the projections 40 communicate with the vertical chamber of the member 35 and permits refrigerant to enter the interior of the shelves which support ice trays. The refrigerant in the shelves increases heat transfer from ice trays supported thereon. A plurality of indentations 45 are provided in the raised portion 38 of plate 36. Similar indentations 46 are provided in raised portion 39 of plate 37. Some of the indentations 45 contact with indentations 46 in the plate 37 while others located on the projections 40 contact with each other. All of the indentations 45 have their contacting surface spot welded together after the plates are assembled together. This or some equivalent operation is desirable to prevent bulging of the sheet metal walls if subjected to high pressure refrigerant.

In the top of each member 35 are one or more and preferably two holes 48 provided in the plate 36. Collars 49 are welded to the plate 36 and have a small portion projecting thru these holes. The major portion however of the collars 49 project upwardly to a point adjacent the opening in the flattened portions 31 on the boiler 10 when the members 35 are placed in assembling relation thereto. These collars 49 have interior screw threads forming the fastening means whereby the members 35 may be attached to the boiler. A washer 51 is preferably placed between the two collars 32 and 49 and a connecting member 52 having screw threads thereon to co-

operate with the screw threads in collar 49 constituting in combination therewith a fastening means for the boiler and the hollow wall members 35. Each of the connecting members 52 have hollow and preferably hexagonal passageways cooperating with the central passageway of the collar 49 to provide means whereby the liquid refrigerant may descend into the separate expansion chambers formed by the hollow wall members 35 connected to the boiler and extending rearwardly therewith. These connections serve to uniformly distribute liquid refrigerant from the boiler to the expansion chambers thereunder which extend rearwardly with the boiler to provide the freezing zone 11. The structure shown presents a large heat absorbing surface that is easily cleaned and affords means for conveniently spot welding the walls 36 and 37 together and provides an efficient distributing system for the liquid refrigerant about the top, sides, and bottom wall of the enclosure 11 and in the shelves supporting the ice trays.

The plates or walls 36 and 37 are also provided with holes 54 which communicate with each other when these plates are secured together. When the members 35 are assembled to the boiler 10 rods 55, having reduced threaded end portions 56, fit into the holes 54. These rods are firmly secured to the evaporator by nuts 57. It is preferable to coat the rods 55 and nuts 57 with a non-rusting material such as chromium. The members 35 are rigidly positioned by the rods 55 which prevent these members from being moved relative to each other which movement if of a sufficient distance might cause loosening of the connecting members 52 from the hollow wall members 35. It is to be understood that the members 35 altho rigidly positioned and secured to the boiler, may be detached therefrom by loosening the connecting members 52 and the nuts 57 from the rods 55. These and other rods may be placed elsewhere about the members 35 and for instance thereabove by providing suitable ears on these members.

The ice trays have fronts 59 secured thereto and provided with handles. These tray fronts 59 preferably extend so close to one another that no additional dividing means is necessary between the trays on the front side of the freezing zone or enclosure 11. If desired the back 61 (see Fig. 5) may be placed on the enclosure or freezing zone by securing corner strips 62 to the rear corners of each member 35 and by placing the bolts or other fastening means 63 thru the back and corner pieces. Thus the interior of the freezing zone is protected from the circulating air within the cabinet which is normally at a relatively higher temperature than that within the enclosure.

The members 35 which form the walls of the freezing zone or enclosure 11 are coated

with a vitreous enamel baked in a high temperature, preferably porcelain, and thus constitutes a beautiful and easily cleaned surface for the enclosure. The tray fronts may be coated or covered also with this vitreous enamel to correspond with the surface of the exterior or they may be instead covered with the same metal of high polishability as that with which the boiler and the connecting collars 49 are plated.

It will thus be observed that I have provided a very efficient evaporator which may be easily cleaned and which occupies a minimum amount of space in a refrigerator cabinet. The evaporator disclosed may be completely concealed within the refrigerator by a baffle or front plate as disclosed in the patent to S. M. Schweller 1,597,625 issued August 24, 1926, altho it is believed that the evaporator is of such pleasing appearance as to warrant the elimination of such front covers. Furthermore this construction provides an evaporator in which substantially the entire cooling surfaces thereof are in intimate thermal contact with liquid refrigerant. It is also apparent that I have provided an evaporator having a freezing zone or enclosure formed by identical sheet metal members which are detachably connected to the header of the evaporator. This construction permits the manufacture of these members in large quantities which reduces manufacturing costs of such evaporators. The detachable connection of these members with the header of the evaporator also permits the removal and replacement of a section only of the walls of the freezing zone. This affords a substantial saving of material and consequently expense should one wall of the freezing zone or enclosure of the evaporator become damaged during manufacture, shipment or service.

While the form of embodiment of the invention as herein disclosed, constitutes a preferred form, it is to be understood that other forms might be adopted, all coming within the scope of the claims which follow.

What is claimed is as follows:

1. An evaporator for refrigerating apparatus including a plurality of sheet metal members detachably held together to provide complementary portions forming a freezing zone, each of said members forming refrigerant expansion chambers separate from one another, said refrigerant expansion chambers having liquid refrigerant inlet and outlet connections, means formed integral with at least one of said members and extending horizontally into said freezing zone to divide the zone into a plurality of sharp freezing compartments.

2. An evaporator for refrigerating apparatus including a plurality of sheet metal members detachably held together to provide complementary portions forming a

freezing zone, each of said members forming refrigerant expansion chambers separate from one another, said refrigerant expansion chambers having liquid refrigerant inlet and outlet connections, means formed integral with each of said members and extending horizontally into said freezing zone a substantial distance to divide the zone into a plurality of sharp freezing compartments.

3. An evaporator for refrigerating apparatus including a plurality of sheet metal members detachably held together to provide complementary portions forming a freezing zone, each of said members forming refrigerant expansion chambers separate from one another, said refrigerant expansion chambers having liquid refrigerant inlet and outlet connections, means formed integral with at least one of said members and extending horizontally into said freezing zone, said means including spaced apart portions forming a refrigerant expansion conduit communicating with the refrigerant expansion chamber in the member from which said means is formed and providing a plurality of superimposed refrigerated supports within said freezing zone for receiving substance to be frozen.

4. An evaporator for refrigerating apparatus including a header forming a reservoir for liquid refrigerant, a plurality of sheet metal members each detachably connected to said header and providing complementary portions forming a freezing zone, each of said members forming refrigerant expansion chambers separate from one another and communicating with said header through said detachable connection, means formed integral with at least one of said members and extending horizontally into said freezing zone to divide the zone into a plurality of sharp freezing compartments.

5. An evaporator for refrigerating apparatus including a header forming a reservoir for liquid refrigerant, a plurality of sheet metal members each detachably connected to said header and providing complementary portions forming a freezing zone, each of said members forming refrigerant expansion chambers separate from one another and communicating with said header through said detachable connection, means formed integral with each of said members and extending horizontally into said freezing zone a substantial distance to divide the zone into a plurality of sharp freezing compartments.

6. An evaporator for refrigerating apparatus including a header forming a reservoir for liquid refrigerant, a plurality of sheet metal members each detachably connected to said header and providing complementary portions forming a freezing zone, each of said members forming refrigerant expansion chambers separate from one another and communicating with said header through said de-

tachable connection, means formed integral with at least one of said members and extending horizontally into said freezing zone, said means including spaced apart portions forming a refrigerant expansion conduit communicating with the refrigerant expansion chamber in the member from which said means is formed and providing a plurality of superimposed refrigerated supports within said freezing zone for receiving substance to be frozen.

7. An evaporator for refrigerating apparatus including a plurality of sheet metal members detachably held together to provide complementary portions forming a freezing zone, each of said members forming refrigerant expansion chambers separate from one another, said refrigerant expansion chambers having liquid refrigerant inlet and outlet connections, means associated with at least one of said members and extending horizontally into said freezing zone to divide the zone into a plurality of sharp freezing compartments.

25 In testimony whereof I hereto affix my signature.

OTTO M. SUMMERS.
